UNITED STATES PATENT OFFICE.

ANTON F. STEINER AND EMMA W. STEINER, OF CRANE, MISSOURI.

DESIGN FOR A CIRCLET.

50,668.

Specification for Design.

Patented Apr. 24, 1917.

Application filed March 4, 1916. Serial No. 82,249. Term of patent 14 years.

To all whom it may concern:

Be it known that we, ANTON F. STEINER and EMMA W. STEINER, citizens of the United States, residing at Crane, in the county of Stone and State of Missouri, have invented a new, original, and ornamental Design for a Circlet, of which the following is a specification, reference being had to the accompanying drawing, forming a part thereof.

The figure is a perspective view of a circlet, showing our design.

We claim:

The ornamental design for a circlet, as shown.

A. F. STEINER.
EMMA W. STEINER.
